UNITED STATES PATENT OFFICE.

CARL H. CRAWFORD, OF SPOKANE, WASHINGTON.

COMBINED CULTIVATOR AND WEEDEER.

1,170,879.

Specification of Letters Patent.

Patented Feb. 8, 1916.

Application filed October 12, 1915. Serial No. 55,427.

To all whom it may concern:

Be it known that I, CARL H. CRAWFORD, a citizen of the United States, residing at Spokane, in the county of Spokane and State of Washington, have invented certain new and useful Improvements in Combined Cultivators and Weeders, of which the following is a specification.

This invention relates to improvements in weeders and cultivators and has to do more particularly with implements of this character employing a rotary rod advancing beneath the surface soil.

It has been found that by rotating a rod and advancing the rod beneath the surface soil, that it not only connects with and pulls up or winds up the roots of weeds but it also packs the sub-soil and loosens the surface soil in such a manner that moisture passes beneath the surface and enters the packed sub-soil where it is most needed by the roots of the plants. Heretofore, the difficulty with machines of this character has been that the rotating rods had a tendency to pull out of the soil and it was necessary to maintain a sustained thrust on the rod to keep it down into the soil.

The essence of the present invention, is to so construct the device that draft pull will be imposed in such a manner as to transmit a depressing thrust on the rod and maintain the rod beneath the surface soil, without any levers or links for performing this function.

A further novel feature consists in applying or transmitting rotary motion to the rod in such a manner that the transmission of rotary motion will impart a downward thrust tending to maintain the rod beneath the surface soil.

A further novel feature consists in regulating the depth of depression of the rod into the surface soil, and in the preferred construction, the regulating means rolls on the soil slightly in advance of the rod so that the desired depth can be accurately ascertained and maintained.

Other features of novelty will be more fully described in connection with the accompanying drawing and will be more particularly pointed out in and by the appended claims.

In the drawing:—Figure 1 is a plan view of a combined cultivator and weeder embodying one form of my invention. Fig. 2 is a sectional view on line 2—2 of Fig. 1.

Like characters of reference designate similar parts throughout the different figures of the drawing.

As illustrated, 1 designates bearing wheels 60 which are mounted upon an axle 2. A frame 3 is tiltably mounted on the axle 2 and extends forwardly therefrom so that the forward portion 4 of the frame will normally act to tilt downwardly by gravity. The frame may be constructed of channel iron and may be rectangular as shown, end members being indicated at 5.

A yoke 6, of substantially U-shaped construction, has its terminals 7 journaled on axle 2 and at the bight of said yoke 6, I attach a tongue 8 by means which may comprise angle irons 9. The bearings 1 will be of such diameter that the tongue 8 will be inclined slightly upwardly, from the axle 2, with respect to the horizontal, especially in the form shown. Furthermore, the tiltable frame will normally tilt downwardly from the longitudinal axis of the draft means, comprising the yoke and tongue. 80

Depending bearing hangers 10 are shown attached to the tilttable frame at 11 and in their lower ends is journaled the combined cultivating and weeder rod 12. The forward terminals of the bearings 10 are knife edged, as indicated at 13, so that they will subdivide the soil and reduce resistance to advancing movement of the bearings beneath the soil surface. A line 14 indicates the soil surface. A line 15 indicates the sub-soil that is packed by the cultivating rod 12. The area 16 is the loosened surface soil above the line of packing soil. 90

Now it will be seen that when the line of draft is applied to the axle, coincident with the inclined tongue 8, that the tilttable frame in addition to its normal action of tilting downwardly with the rod 12, will have imparted thereto a thrust which will tend to bury the rod 12 into the soil. It is thus a feature of my invention to employ the draft to impart thrust to the rod 12 to bury the same in the soil. Now in order to regulate the depth of the rod 12, I provide means which may comprise caster rollers 17 mounted in forks 18 which are rotative in bearings 19. Bearings 19 are shown mounted upon arms 20 attached to the forward frame member 4, at 21. Now it is a feature of my invention, to dispose the caster rollers 17, in advance of the rod 12, so that if broad caster rollers, are used, they will not tend 100

105

110

to mash down the upper loose soil 16. Furthermore, by extending the casters considerably forwardly of the tilttable frame, the leverage is such that they can easily hold up 5 the frame against excessive downward tilting movement without greatly increasing the drag on the implement. However, I do not wish to be limited to this particular means of supporting the tilttable frame as 10 the latter might be suspended from the tongue, if desired.

Means is provided for transmitting rotary motion to rod 12, and in the present construction, such means may comprise gear 15 wheels 22, mounted on axle 2, and meshing with gear wheels 23 mounted upon the tilttable frame. Flexible shafting 24 connects the wheels 23 with the rod 12 to rotate the latter.

20 Now it will be seen by reference to Fig. 2, that when the gear wheel 22 rotates in a clockwise direction, it will not only rotate gear wheel 23, but in so doing, it will impart a downward thrust through gear wheel 25 23 to the tilttable frame to normally act to tilt the frame downwardly. Thus it will be seen that I not only tilt the frame downwardly by the draft imparted to the implement, but I also tilt the frame downwardly by rotary transmission imparted to 30 the rod 12. I consider these features novel singly, and together.

If there should be any tendency of the bearing wheels 1 to tilt up about the rod 12 35 as a fulcrum, or pivot, I provide means for counteracting any such tendency which may comprise a retainer 25, fixed to the tongue 8, as shown at 26, and extending rearwardly to a point above member 3 of the tilttable 40 frame. I may interpose a spring 27 between the terminal end of the retainer and the frame member 3 so that the latter will always be engaged. However, by disposing the rollers 17, forwardly of the rod 12, these 45 rollers themselves will counteract any tendency of the draft to lift the frame about rod 12 as a fulcrum. Furthermore, if the implement is desired as a riding implement, the feet of the rider may extend rearwardly 50 from the frame member 3, so that the rider's weight will hold the bearing wheels down against upward tilting movement.

Weeders of this character, are only used in soil which has been cleared very thoroughly and therefore it is not necessary to contemplate engagement of the rod 12 with rocks and stumps of partially cleared land.

Agriculturists of scientific standing, have clearly determined the great advantage of 60 loosening the surface soil so as to let moisture down through the loosened surface soil, and packing the sub-soil so as to retain the moisture at a point below the surface, which is at an elevation under the surface soil of 65 most advantage to the roots of plants. Fur-

thermore, it has been demonstrated by considerable use, that a rod rotating beneath the surface soil, will wind up the roots of weeds in such a manner as to effectively exterminate the latter.

70 While I have herein shown and described one specific form of my invention, I do not wish to be limited thereto except for such limitations as the claims may import.

I claim:

75 1. As a means for weeding and cultivating soil, a bearing structure including bearing wheels, a weeding and cultivating rod carried by said structure, and means causing said rod to be depressed beneath the soil surface on forward movement of said structure, substantially as described.

80 2. As a means for weeding and cultivating soil, a bearing structure including bearing wheels, a weeding and cultivating rod carried by said structure, means causing said rod to be maintained beneath the soil surface on forward movement of said structure, and means for limiting the depth of depression of said rod, substantially as described.

85 3. As a means for weeding and cultivating soil, a bearing structure including bearing wheels, a weeding and cultivating rod journaled on said structure, and mechanism transmitting rotary drive to said rod to depress the latter into and rotate the same beneath the soil surface, substantially as described.

90 4. As a means for weeding and cultivating soil, a bearing structure including bearing wheels, a weeding and cultivating rod journaled on said structure, mechanism transmitting rotary drive to said rod to depress the rod below the surface soil and rotate the rod, and means causing said rod to 10 be maintained beneath the surface soil on forward movement of said structure, substantially as described.

95 5. As a means for weeding and cultivating soil, bearing wheels, a frame rotatably mounted on said wheels to tilt downwardly forwardly of the axes of said wheels, a rod journaled in said frame forwardly of the axes of said wheels, and means applying draft rearwardly of said rod to depress the 11 latter into the soil, substantially as described.

100 6. As a means for weeding and cultivating soil, bearing wheels, a frame rotatably mounted on said wheels to tilt downwardly forwardly of the axes of said wheels, a rod 12 journaled in said frame forwardly of the axes of said wheels, means for applying draft at the axes of said wheels to depress said rod below the soil surface, and means mounted on said frame for regulating the 12 extent of depression of said rod, substantially as described.

105 7. As a means for weeding and cultivating soil, bearing wheels, axles for said wheels, a frame mounted on said axles and project-

ing forwardly to tilt downwardly, a rod journaled on said frame, means for transmitting motion from said wheels to rotate said rod and impart downward thrust to 5 said frame to depress the rod into the soil, a caster supporting said frame against successive tilting movement, a draft yoke and tongue pivotally connected with said axles and extending forwardly of said frame to 10 exert downward tilting thrust on said frame when draft is applied to said axles, and a device carried by said tongue for engagement with said frame to prevent upward movement of said bearing wheels, substantially 15 as described.

8. As a means for weeding and cultivating soil, bearing wheels, means for advancing said wheels, a frame tiltably mounted on said wheels and projecting forwardly therefrom to move downwardly by gravity, and a weeding rod journaled in said frame to be depressed beneath the soil surface by downward gravity movement of said frame and advancing movement of the latter, substantially 25 as described.

9. As a means for weeding and cultivating soil, bearing wheels, a frame floatingly mounted on said wheels to tilt downwardly by gravity, a weeding cultivating rod journaled on said frame, and draft means applying draft to said wheels at an upward

incline with respect to said frame whereby draft thrust will be transmitted to said frame to depress the latter and maintain said rod below the soil surface, substantially 35 as described.

10. In a weeder, a weeder rod, and structure means automatically forcing said rod beneath the soil surface as said means is moved along the soil, substantially as described. 40

11. In a weeder, a weeder rod, and carrying structure draft propelled means automatically forcing said rod beneath the soil surface as said means is moved along the soil, substantially as described. 45

12. In a weeder, a weeder rod, a structure for pushing said rod into the soil surface as said structure is advanced along the soil, means positioned to rest on the surface of the soil for limiting depression of said rod, and means for transmitting rotary motion to said rod, substantially as described. 50

13. In a weeder, a weeder rod, a carrying structure for forcing said rod below the soil surface as said structure is moved along the soil, said structure having bearing wheels tracking rearwardly of said rod, and means for rotating said rod, substantially as described. 55

In testimony that I claim the foregoing as my own, I hereby affix my signature.

CARL H. CRAWFORD.
